(57) **CLAIM**

The ornamental design for an electrical power distribution unit, as shown and described.

DESCRIPTION

FIG. 1 is a top, front, left perspective view of an electrical power distribution unit showing our new design, according to a first embodiment;

FIG. 2 is a top, rear, left perspective view thereof;

FIG. 3 is a bottom, rear, left perspective view thereof;

FIG. 4 is a front elevation view thereof;

FIG. 5 is a rear elevation view thereof;

FIG. 6 is a right side elevation view thereof;

FIG. 7 is a left side elevation view thereof;

FIG. 8 is a top plan view thereof;

FIG. 9 is a bottom plan view thereof;

FIG. 10 is a top, front, right perspective view of another electrical power distribution unit showing our new design, according to a second embodiment;

FIG. 11 is a bottom, front, left perspective view thereof;

FIG. 12 is a bottom, rear, right perspective view thereof;

FIG. 13 is a front elevation view thereof;

FIG. 14 is a rear elevation view thereof;

FIG. 15 is a right side elevation view thereof;

FIG. 16 is a left side elevation view thereof;

FIG. 17 is a top plan view thereof; and,

FIG. 18 is a bottom plan view thereof.

The broken lines and the portions within are for the purpose of illustrating portions of the article that form no part of the claimed design.

1 Claim, 6 Drawing Sheets
